UNITED STATES PATENT OFFICE.

GEORGE W. WILEY, OF ESTHERVILLE, IOWA.

DRAFT-EQUALIZER.

No. 805,250.

Specification of Letters Patent.

Patented Nov. 21, 1905.

Application filed July 18, 1905. Serial No. 270,248.

To all whom it may concern:

Be it known that I, GEORGE W. WILEY, a citizen of the United States, residing at Estherville, in the county of Emmet, State of Iowa, have invented certain new and useful Improvements in Draft-Equalizers; and I do hereby declare the following to be a full, clear, and exact description of the invention, such as will enable others skilled in the art to which it appertains to make and use the same.

This invention relates to draft-equalizers, and has for its object to provide a device of this kind with which the draft of several horses attached to a vehicle may be equalized and which will include a novel arrangement of parts permitting of the adjustment of the equalizer to suit different conditions.

Other objects and advantages will be apparent from the following specification, which describes an embodiment of the present invention.

In the drawings forming a portion of this specification and in which like characters of reference indicate similar parts in the several views, Figure 1 is a top plan view of the present equalizer. Fig. 2 is a bottom view. Fig. 3 is a longitudinal section. Fig. 4 is a detail section on line 4-4 of Fig. 2. Fig. 5 is a top plan view of a modified form of the invention.

Referring now to the drawings, there is shown a draft-pole 6 of a vehicle, to the under side of which there is secured a longitudinally-extending casting 7. In the rearward portion of this casting there is a transversely-extending passage 8, and projecting laterally from the casting in an opposite direction there are pairs of horizontally-extending wings 9 and 10, these wings extending outwardly above and below the passage 8. Slidably engaged in the passage 8 there is a transverse member 11, having a longitudinally-extending series of perforations 12 therein, and the wings of each pair are provided with registering perforations 13, adapted for interchangeable registration with the perforations 12, the casting itself being provided with an opening 14, communicating with its under face and with the passage 8 and registering with a threaded recess 15 in the upper wall of the passage for the reception of a pin 16, this pin having a threaded end which enters the threaded recess, and this pin is adapted for engagement in the perforations 12 interchangeably for pivotal movement of the member 11 thereupon, and it will thus be apparent that the member may be moved longitudinally

through the passage 8, the pin 16 being shifted to different perforations of the member to adjust this portion of the equalizer, and it will be understood that the pin 16 may be removed from the perforations 14 and the recess 15 and engaged in the registering perforations of one of the pairs of ears and in one of the perforations 12 to shift the pivot-point of the member 11 to one side of the tongue 6, the dimension of the passage 8 longitudinally of the tongue being such as to permit of lateral movement of the member 11 therewithin.

When it is desired to hold the member 11 against pivotal movement, an additional pin may be disposed in one of the registering pairs of perforations and in one of the perforations 12, which will produce the desired result, as will be readily understood.

Brackets 17 and 18 are secured to the under face of the draft-pole 6 and extend laterally beyond one side thereof, the bracket 17 being located forwardly of the bracket 18, and pivoted at its inner end in the bracket 17 there is a laterally-extending horizontal arm 19, having a whiffletree 20 connected thereto at its forward side.

An arm 21 is pivoted in the bracket 18 at one end and extends oppositely to the arm 19 and beneath the draft-pole 6, a guide 22 for the arm 21 being secured to the under face of the draft-pole. The arm 21 has a whiffletree 23 connected thereto at its forward side, and a link 24 is pivotally connected with the arm 21 and with the portion of the member 11 lying at the same side of the draft-pole, a rod 25 being similarly connected with the opposite end portion of the member 11 and with the arm 19, and these rods 24 and 25 are shiftable longitudinally of the elements to which they are connected to vary the leverage, the rods having angular ends 26, removably engaged in perforations 19' and 21' of the arms 19 and 21, respectively, and also in the perforations 12 of the member 11.

In Fig. 5 there is shown a modified form of the invention, in which the draft-pole 6 is replaced by a short supporting-beam A, to which the arms and member are connected in the manner described and having a clevis B at its rearward end, this form of the invention being especially adapted for use in connection with plows.

What is claimed is—

1. In a draft-equalizer the combination with a support, of a transverse member pivotally

- connected with the support, said member being shiftable longitudinally, a laterally-extending arm pivoted at one side of the support, connections between said arm and one end of the member, a second arm pivotally connected with the support at the same side as the first-named arm and extending beyond the opposite side of the support, connections between the second arm and the other end of the member, said connections being arranged for movement of the two arms and the member simultaneously and being shiftable longitudinally of the arms and member, and attaching devices carried by the arms.
- 15 2. In a draft-equalizer the combination with a support, of a casting secured to the support and having a passage extending transversely of the support, a member disposed in the passage and having a longitudinal series of perforations therein, oppositely-extending pairs of lateral wings carried by the casting and lying above and below the member, the wings of each pair having registering perforations therein, a pin removably engaged in the casting and in one of the perforations of the member, the perforations of the wings being adapted to receive a pin engaged in a perforation

of the member, oppositely-extending arms pivoted to the support and connections between the arms and the member for simultaneous movement thereof, said arms being adapted for the attachment of draft-animals thereto.

3. In a draft-equalizer the combination with a support, of a casting secured to the support, 35 a transversely-extending member pivoted in the support and arranged for longitudinal adjustment, means for holding the member against pivotal movement, laterally-extending brackets carried by the support at one side 40 thereof, oppositely-extending lateral arms pivoted in the brackets, one of said arms extending beneath the support and beyond the opposite side thereof, a guide for said arm and connections between the arms and the member 45 at opposite sides of the support, said connections being shiftable longitudinally of the arms and member.

In testimony whereof I affix my signature in presence of two witnesses.

GEORGE W. WILEY.
